UNITED STATES PATENT OFFICE

129,911

DESIGN FOR A BRIDGE FOR AN
OPHTHALMIC MOUNTING

Theodore R. Uhlemann, Antioch, Ill., assignor to
Uhlemann Optical Co. of Illinois, Chicago, Ill.,
a corporation of Delaware

Application April 5, 1940, Serial No. 91,488

Term of patent 3½ years

To all whom it may concern:

Be it known that I, Theodore R. Uhlemann, a citizen of the United States, residing at Antioch, in the county of Lake and State of Illinois, have invented a new, original, and ornamental Design for a Bridge for an Ophthalmic Mounting, of which the following is a specification, reference being had to the accompanying drawing, forming a part thereof, in which

Figure 1 is a perspective view of a bridge for an ophthalmic mounting, showing my new de-

sign, the essential features of which are shown in full lines;

Fig. 2 is a plan view of the disclosure in Figure 1;

Fig. 3 is a section on the line 3—3 of Fig. 2. I claim.

The ornamental design for a bridge for an ophthalmic mounting, substantially as shown and described.

THEODORE R. UHLEMANN.
